[57] CLAIM

The ornamental design for a door annunciator housing,
as shown and described.

DESCRIPTION

FIG. 1 is a perspective view of a door annunciator housing showing my new design;
FIG. 2 is a front elevational view thereof;
FIG. 3 is a side elevational view thereof, the opposite side being a mirror-image of FIG. 3;
FIG. 4 is a back elevational view thereof; and
FIG. 5 is a top plan view thereof, the bottom plan view
being a mirror-image of FIG. 5.

FIG. 1

FIG. 2

FIG. 3

FIG. 4

FIG. 5
